UNITED STATES PATENT OFFICE.

GEORGE B. REED, OF PHILADELPHIA, PENNSYLVANIA.

METHOD OF AND APPARATUS FOR ENGINE-BRAKING.

1,300,016.

Specification of Letters Patent.

Patented Apr. 8, 1919.

Application filed August 24, 1917. Serial No. 187,999.

To all whom it may concern:

Be it known that I, GEORGE B. REED, a citizen of the United States, residing in Philadelphia, county of Philadelphia, and State of Pennsylvania, have invented new and useful Improvements in Methods of and Apparatus for Engine-Braking, of which the following is a specification.

My invention relates to a method of and 10 means for braking an engine, and thereby braking apparatus driven by it, as for example, an automobile or other vehicle, hoisting or elevator apparatus, etc.

My invention resides in braking means of 15 the character referred to whereby elastic fluid, such as steam, air or gas, is introduced into and confined in the cylinder of the engine to there oppose the piston and resist its movement, the fluid being compressed 20 by the piston and allowed to escape at suitable time and rate, as through the valve mechanism of the engine.

More particularly my invention resides in 25 such method and apparatus for braking an engine of the uni-flow type.

My invention resides also in mechanism 30 for suitably graduating the braking effect and in suitable mechanism for controlling and changing the path of flow of the elastic fluid.

For an illustration of one example of my invention, reference is to be had to the accompanying drawing, in which:

Figure 1 is a side elevational view, partly 35 in section, of the principal parts of a uni-flow engine equipped for braking.

Fig. 2 is a fragmentary sectional view, on enlarged scale, through the slide valve mechanism and associated parts.

Fig. 3 is a cross sectional view, some parts 40 in plan, taken on the line 3-3 of Fig. 2.

Fig. 4 is a fragmentary sectional view taken on the line 4-4 of Fig. 2.

Fig. 5 is a fragmentary sectional view, 45 some parts in elevation, of controlling valve mechanism.

Fig. 6 is a fragmentary sectional view indicating structure of the throttle valve.

Referring to the drawings, S is the engine 50 shaft, rotated by the engine and in turn driving the load, which may be a vehicle or automobile. Secured upon the shaft S is the crank a having thereon the crank pin

b upon which is journaled one end of the connecting rod c whose other end is pivoted at d upon the cross head e, movable longitudinally in the cross head guides f, f. To the cross head e is secured the piston rod g extending into the engine cylinder C and carrying at its end the piston P.

Upon the shaft S are the usual eccentrics h, h, as of a Stevenson link motion L, or any other suitable mechanism, for reciprocating the cross head i and for determining its extent of movement and phase relation with respect to the piston P. The cross head i actuates the valve stem j which extends into the interior of a steam chest k where it is secured to the slide valve frame m having at its other end the guide rods n, n. In openings o, o in the valve frame m are disposed the loosely fitting valve members p, p having the ports q, q adapted to communicate with the cylinder ports r, r in communication through the passages r', r' with the ports s, s opening into the interior of the cylinder C at opposite ends thereof.

Disposed above the slide valve members p, p is the plate t pivoted at u, u to the sleeve member v having a longitudinal bearing upon the eccentric w upon the shaft x which extends to the exterior of the valve or steam chest k and is attached to the rotary member of the throttle valve T, Figs. 1 and 6, actuated by the operating lever y. The plate t has ports or openings t¹, t¹ with which and the ports r, r the ports q, q are adapted to communicate.

Communicating with the interior of the steam or valve chest k is the pipe z communicating at its other end, Figs. 1 and 5, with the interior of the valve casing a¹, with the interior of which the pipe b¹, controlled by throttle valve T, communicates through the port c¹. Movable longitudinally within the valve casing a¹ is the valve member d¹ actuated by the rod e¹ which is in turn actuated by the hand lever f¹.

Communicating with the interior of the cylinder C at substantially mid-way of its length is the exhaust port E to which connects the pipe g¹ which at its other end communicates with the interior of the valve casing a¹ on that side of the port c¹ opposite to the pipe z. Adjacent the casing a¹ the pipes z and g¹ are connected through the pipes h¹

and z^1 with the pipe j^1 , a valve k^1 determining which of the pipes z or g^1 shall communicate with the pipe j^1 . The valve k^1 is actuated through any suitable connections, as the links m^1 and n^1 , by the operating lever f^1 .

The operation is as follows:

The pipe b^1 is connected with a suitable source of motive fluid, for example, a steam boiler. The valve lever y is actuated in direction to open the throttle valve T , thereby allowing steam to flow through the pipe b^1 to the valve casing a^1 , through the port c^1 , thence into the casing a^1 to the right of the valve member d^1 into the pipe z , to the steam or valve chest k of the engine, the valve k^1 , due to its interconnection with the valve d^1 , being in position to prevent communication between the pipe z and the exhaust pipe j^1 . Accordingly steam will pass, in the position illustrated, to the left end of the cylinder C through the left hand valve member p whose port q is in register with the left hand port r . This causes the piston P to be forced toward the right, Fig. 1, to rotate the shaft S which drives the vehicle or other load and simultaneously actuates the valve rod j in suitable phase relation and through suitable stroke as determined by the link motion L , which, it will be understood, is merely indicated diagrammatically and may be of any well known type. The piston P passes over the port E communicating with the pipe g^1 and when reaching the opposite end of the cylinder C uncovers that port, with the result that the steam which has driven the piston P forward exhausts into the pipe g^1 past the valve k^1 to the exhaust pipe j^1 . When the piston P reaches the right hand end of the cylinder the right hand valve member p admits steam into the right hand port r which then causes steam to enter the right hand end of the cylinder C to force the piston P backwardly in opposite direction to further rotate the shaft S in well known manner, and when reaching the position illustrated the steam is exhausted again through the pipe g^1 , valve k^1 and exhaust pipe j^1 .

In general the foregoing description is that of the operation of a uni-flow engine. This cycle of operations is repeated, causing the continuous rotation of the shaft S , for example in the direction indicated by the arrow.

Assuming that the engine drives an automobile or other vehicle through suitable connections from the shaft S to the wheels of the vehicle, the upper end of the operating lever f^1 , Fig. 1, is shifted toward the right, thereby moving the valve member d^1 toward the right in the casing a^1 to close communication between the port c^1 and the pipe z and to open communication between the port c^1 and the pipe g^1 and simultaneously shifting the valve k^1 to close communication between

pipes g^1 and j^1 and to open communication between the pipe z and the pipe j^1 . Then the throttle valve T , which previously may have been closed, is opened by operation of the lever y , whereupon steam will again pass through the pipe b^1 through the port c^1 into the casing a^1 to the left of the now shifted valve d^1 and into the pipe g^1 , formerly an exhaust pipe, into the cylinder C through the port E to one side of the piston P . The presence of the fluid in the cylinder C on that side of the piston P which in normal operation of the engine would be the exhaust side, opposes the movement of the piston P and so causes exertion upon the shaft S of resistance to the force exerted upon the shaft S by the moving vehicle, thereby exerting a retarding or braking effect upon the vehicle. As the piston P moves farther and farther toward one end of the cylinder, it compresses the steam lately admitted through the port E , and this steam eventually escapes through the cylinder port s , passage r' and port r , through the slide valve into the steam chest k and out through the pipe z , thence past the valve k^1 to the exhaust pipe j^1 . By the time the piston P has so operated in compressing the steam and has moved to one end of the cylinder, the steam is admitted from pipe g^1 through port E to the opposite side of the piston and opposes it in its return stroke, and the steam is again compressed and eventually allowed to escape through the now properly positioned slide valve p into the chest k and through the pipe z into the exhaust pipe j^1 , this action being cyclically repeated, causing progressive braking or retardation of the engine and of the vehicle driven thereby without reversing the engine.

The steam from the cylinder C in the braking operation tends to lift the valve members p , p and to escape into chest k . The lifting of the valve members p , p is, however, limited and controlled by the plate t actuated by the valve lever y . As the throttle valve T is opened wider and wider in the braking operation, admitting more and more steam into the cylinder C and causing greater and greater pressures on the under side of the valve members p , p , they are held to the valve seat o^1 more and more closely by the plate t , which descends as valve T opens, thus correspondingly restricting the egress of the braking steam from the cylinder C and interposing greater and greater resistance to its escape into chest k .

In other words, when a small amount of steam is admitted into the cylinder through the pipe g^1 due to slight opening of the throttle valve T , it is compressed by the piston P , which soon shuts off the steam supply by covering the cylinder port E to which the pipe g^1 connects, and this compressed steam escapes through the slide valve mechanism into the chest k as previously

described, with comparative freedom, because of the freedom of the valve members p , p to lift. But as the braking effect is increased by further opening of the throttle 5 valve T , the valve members p , p are held more and more closely to the valve seat o^1 , and so reducing the freedom of escape of braking steam from the cylinder C during the period before free exhaust through the 10 passage g .

Accordingly by the control described a graduated braking effect is procured.

Variations in the stroke of the slide valves p , p or variations of the point of cut-off as 15 determined by the link motion L will have little effect upon the braking action, since the amount of braking steam to be exhausted from the cylinder C will never be great at high speed, and at low speed there will be 20 ample time for exhaust of such steam even when the period of communication between a cylinder port and the valve chest h is short.

And the braking action is available also when the engine is running in opposite direction to that hereinbefore indicated, such reverse movement of the engine being accomplished in well known manner by shifting the link motion L by handle lever h^2 which also controls the point of cut off.

30 This mode of retarding or braking an engine or motor differs from merely reversing the engine in that, in accordance with my method, elastic fluid is admitted to the cylinder at substantially the end of the forward stroke of the piston which in returning compresses the now entrapped steam which may reach a pressure higher than the pressure of the source, and a repetition of the action in the successive strokes will at most bring the 35 engine to rest and will never cause its operation in reverse direction. On the other hand, however, when reversing an engine, the elastic fluid is admitted in such way as to tend to drive the engine in reverse direction, and the elastic fluid opposing the return stroke of the piston never exceeds the pressure of the source, and as the operation continues, will actually reverse the direction of movement of the engine or motor.

40 While the foregoing description relates more particularly to a motor or engine of the uni-flow type, it is to be understood that the same principle is applicable to the common type of engine in which the valve mechanism is such that steam is both admitted and exhausted through ports substantially at the ends of the cylinder.

And while I have hereinbefore indicated the application of the braking method and 45 apparatus to motor vehicles, it will be understood to be of general application, including the braking of engines driving mine or other hoists, elevators, etc.

What I claim is:

60 1. The method of braking a reciprocating

engine while continuing to run in predetermined direction, which consists in admitting elastic fluid from a source thereof to the cylinder at substantially the end of the forward stroke of the piston, isolating the 70 admitted fluid from said source during return stroke of said piston, converting kinetic energy of the system into pressure of said fluid by compressing the entrapped fluid by the return stroke of said piston, and releasing said compressed fluid. 75

2. The method of braking a reciprocating engine while its valve gear is set in position for continued running in normal direction, which consists in admitting elastic 80 fluid from a source thereof to the cylinder at substantially the end of each of the forward strokes of the piston, entrapping and isolating the fluid from said source and compressing the same by the return strokes of 85 said piston, and releasing the compressed fluid at substantially the end of each return stroke.

3. The method of braking a reversible reciprocating steam engine without shifting 90 its reversing valve gear, which consists in admitting steam from a source thereof to the cylinder through the normal exhaust port at substantially the end of the forward stroke of the piston, absorbing kinetic energy of the system by compressing the steam while entrapped and isolated from said source in the cylinder by the return stroke of the piston, and releasing the compressed steam through the normal inlet port at substantially the end of the return stroke of the 95 piston. 100

4. The method of braking a uni-flow engine while continuing to run in predetermined direction, which consists in admitting 105 elastic fluid to the cylinder at substantially the end of the forward stroke of the piston through the normal exhaust port substantially at the center of the cylinder, absorbing kinetic energy of the system by compressing said fluid while entrapped in the cylinder by the return stroke of the piston, and releasing the compressed fluid through the normal inlet port at substantially the 110 end of the return stroke of the piston. 115

5. The combination with a uni-flow engine comprising a cylinder, valve mechanism controlling communication with opposite ends of the cylinder, said cylinder having a central exhaust port, and means for connecting said valve mechanism to exhaust and for connecting said exhaust port with a source of fluid, whereby fluid admitted through said exhaust port into said cylinder on opposite sides of the piston is compressed thereby to brake the engine and thereafter exhausted through said valve mechanism. 120

6. The combination with a uni-flow engine comprising a cylinder, valve mecha- 130

nism controlling communication with opposite ends of the cylinder, said cylinder having a central exhaust port, of means for connecting said exhaust port with a source 5 of fluid, whereby fluid is admitted into said cylinder on opposite sides of the piston to retard the same, means whereby said valve mechanism allows periodic exhaust of said fluid, and means for increasing the resistance 10 offered by said valve mechanism to escape of said fluid from said cylinder with increase in the quantity of fluid admitted into said cylinder through said exhaust port.

7. The combination with a uni-flow engine comprising a cylinder, valve mechanism controlling communication with opposite ends of the cylinder, said cylinder having a central exhaust port, a valve for admitting fluid through said exhaust port into 15 said cylinder for opposing movement of the piston, means allowing escape of said fluid through said valve mechanism after compression by said piston, means controlling the resistance offered by said valve mechanism to escape of fluid from said cylinder, and means for controlling said last named means and said valve in unison.

8. The combination with a uni-flow engine comprising a cylinder, valve mechanism controlling communication with opposite ends of the cylinder, said cylinder having a central exhaust port, of a second valve mechanism for reversing direction of flow 30 of fluid to and from said cylinder through said exhaust port and said first named valve mechanism.

9. The combination with a uni-flow engine comprising a cylinder, valve mechanism controlling communication with opposite ends of the cylinder, said cylinder having a central exhaust port, of a second valve mechanism for reversing direction of flow 40 of fluid to and from said cylinder through said exhaust port and said first named valve mechanism, and a throttle valve intervening between said second valve mechanism and a source of fluid.

10. The combination with a uni-flow engine comprising a cylinder, valve mechanism controlling communication with opposite ends of the cylinder, said cylinder having a central exhaust port, of a second valve mechanism for reversing direction of flow 50 of fluid to and from said cylinder through said exhaust port and said first named valve mechanism, a throttle valve intervening between said second valve mechanism and a source of fluid, and means actuated in unison with said throttle valve for increasing the 55 resistance to escape of fluid from said cylinder through said first named valve mechanism as the opening of said throttle valve is increased.

11. The combination with a uni-flow engine comprising a cylinder, valve mecha-

nism controlling communication with opposite ends of the cylinder, said cylinder having a central exhaust port, said valve mechanism comprising a reciprocating frame, ported valve members disposed loosely in 70 said frame and adapted to lift from their seats, a ported member above said valve members, of a second valve mechanism for reversing the direction of fluid flow to and from said cylinder through said exhaust port and said first named valve mechanism, and means for varying the distance of said ported member from the seats of said ported valve members.

12. The combination with a uni-flow engine comprising a cylinder, valve mechanism controlling communication with opposite ends of the cylinder, said cylinder having a central exhaust port, said valve mechanism comprising a reciprocating frame, ported 80 valve members disposed loosely in said frame and adapted to lift from their seats, a ported member above said valve members, of a second valve mechanism for reversing the direction of fluid flow to and from said cylinder through said exhaust port and said first named valve mechanism, means for varying the distance of said ported member from the seats of said valve members, a throttle valve intervening between the source 90 of fluid and said second valve mechanism, and means for actuating said throttle valve and said last named means in unison for decreasing the distance of said ported member from the valve seats as the opening of said 100 throttle valve increases.

13. The combination with an engine comprising a cylinder and a piston reciprocating therein, of means for braking the engine comprising a source of fluid, valve mechanism for admitting fluid into the cylinder at substantially the end of the forward stroke of the piston and for isolating the same from said source and entrapping said fluid within said cylinder during the return stroke of the piston, whereby said fluid is compressed, said valve mechanism comprising structure allowing escape of the compressed fluid.

14. The combination with an engine comprising a cylinder and a piston reciprocating therein, of valve mechanism for controlling normal operation of said engine, means cooperating with said valve mechanism to reverse said engine, and means for braking 115 said engine without operation of said reversing means comprising valve structure co-operating with said valve mechanism for admitting fluid from a source thereof into said cylinder at substantially the end of the forward stroke of the piston and for isolating the same from said source and entrapping and compressing the fluid during the return stroke of the piston, whereby said fluid is compressed, said valve mechanism 120

125

130

allowing escape of the compressed fluid at substantially the end of the return stroke of the piston.

15. The method of braking a reversible uniflow engine without actuation of its reversing gear, which consists in admitting elastic fluid to the cylinder at substantially the end of the forward stroke of the piston through the normal exhaust port substantially at the center of the cylinder, isolating and entrapping said fluid in the cylinder and compressing the same during the return

stroke of said piston to absorb kinetic energy from the system, partially releasing the compressed fluid during the return stroke of 15 said piston, and releasing the compressed fluid through the normal inlet port at substantially the end of the return stroke of the piston.

In testimony whereof I have hereunto af- 20 fixed my signature this 3rd day of Aug., 1917.

GEORGE B. REED.
